FLIER CONSTRUCTION

Michael J. McHale, Scranton, Pa.

Application April 7, 1931, Serial No. 528,442

8 Claims. (Cl. 117—23)

This invention relates to improvements in flier blocks and more particularly to a novel detachable anti-balloonning device for spinning machines.

5 Hitherto it has been proposed to use so-called Figure 8 fliers for preventing ballooning of the threads on a spinning machine. These devices are usually hand made and are formed directly on the flier block with which they are to be used and, 10 usually, are formed integral with the flier arms. When it is desired to replace the Figure 8 flier unit with the straight arm or drop arm type or vice versa it is necessary to remove the wires from the block and rewire. This procedure requires 15 the removal of the fliers to a separate bench or machine shop and renders the machine either temporarily idle or requires the substitution of other blocks during the rewiring.

It is an object of this invention to provide an 20 improved demountable anti-balloonning device for spinning machine fliers.

It is another object of this invention to provide such an improved anti-balloonning device which may be readily inserted and removed from a flier.

25 Yet another object of this invention is the provision of an improved anti-balloonning device which is susceptible of various configurations.

Still another object of this invention is the provision of an improved detachable anti-balloonning device providing a minimum of thread-bearing contact.

These and other desirable objects and advantages of the present invention will be described in the accompanying specification and illustrated 35 in the drawing, certain preferred embodiments being shown by way of example only for, since the underlying features may be incorporated in other specific mechanical devices it is not intended to be limited to the ones here shown except 40 as such limitations are clearly imposed by the appended claims.

In the drawing like numerals refer to similar parts throughout the several views of which

Fig. 1 is an elevation of a bobbin with an attached flier and an improved anti-balloonning member;

Fig. 2 is a top plan view of structure shown in Fig. 1;

Fig. 3 is an elevation of the anti-balloonning 50 device shown in Figs. 1 and 2;

Figs. 4, 5 and 6 are views similar to those shown and show a modified form of anti-balloonning devices.

Broadly considered the novel improvements of 55 the present invention comprehend the utilization

of a detachable guiding member or anti-balloonning device for use in connection with flier constructions, more particularly of the type shown and described in my applications Serial Nos. 458,210, filed May 31, 1930; 458,211, filed May 31, 60 1930; 458,212, filed May 31, 1930; 489,401, filed Oct. 17, 1930; and 507,676, filed January 9, 1931.

Referring now to the drawing there is shown a bobbin 1 mounted for rotation on spindle 2, with which is associated a flier 3 of any desired 65 construction and which as shown in Fig. 1 may comprise a block having a wire retaining platform 4 adapted to receive a flier wire 5, the latter being held in position by means of a clamping member 6. The flier block shown may include a footed member of the eccentric foot type as shown in my applications Serial Nos. 458,212 and 489,401, above referred to or of a concentric foot of the type shown in my application Serial 70 No. 517,023. If desired the flier block may be 75 of the general type shown in Fig. 4 comprising a hub 7 with a wire retaining skirt 8 provided with opposed slots 9 adapted to maintain a flier arm 5 in operative position. These blocks may, as usual, comprise footed members adapted for 80 use with bobbins having locking bushings in the top thereof or may include spring means adapted for retaining the blocks on uniformly tapered spindles. These constructions are severally shown in my applications above identified and 85 are not claimed herein except in the novel combinations hereinafter to be set forth.

Referring more particularly to Figs. 1, 2 and 90 3 the anti-balloonning device of the present invention comprises a top body portion 10 which is so configured as to present substantially a figure 95 S, designated generally by the numeral 11 with parallel side arms 12 bent back from the ends of the S and forming with the legs thereof a substantially rectangular member having spaces 13 between the side members opening into thread receiving channels or apertures 14. The members 12 are continued to form depending legs 15 of any suitable length which terminate in angular extensions 16 adapted for locking engagement with a flier block. As shown in Fig. 1 the locking engagement may be by means of a clamping member 6 or, as shown in Fig. 4, the members 16 may be inserted into apertures 9 of 100 block 7 and be held in position by means of their own resilience, these retaining members being of sufficient length to secure the desired result. By varying the angularity of members 16 with respect to member 15 they may be sprung into 105 110

position and held, as above noted, by their own resilience.

Thread receiving loops of the flier arms 5 cooperate with the sections 14 of the member 10 5 to provide the desired tension for the thread and prevent its ballooning during the spinning operation. The threads may be usually slipped into place through the apertures 13 without requiring any threading. It will be noted that with 10 the construction shown a minimum of bearing contact on the supports 15 is provided for the threads thus preventing any oil or dust which may be accumulated thereon from being picked up by the thread in its travel and thus be incorporated into the finished woven product.

The construction described, can readily be made from wire of any suitable size and is characterized by the ease of attachment and detachment without requiring the formation of an entire new anti-balloon device and flier arm as 20 has heretofore been required. These members may be pre-formed as are the flier arms and permit a marked degree of flexibility in spinning operations which has not heretofore been possible.

While the construction shown in Figs. 1, 2 and 3 may be used, when desired, the invention also comprehends the use of looped members similar in construction to those shown, with the 30 exception that the thread receiving or guiding portion is formed by a loop 20 formed integral in the wire. These loops are shown more particularly in Figs. 4 to 6 inclusive, the remainder of the structure being similar to that already described.

Any desired configuration may be given to the sections 10 and 20 of the anti-balloon devices and it will be appreciated that the retaining means may also be varied. The retaining means 40 associated with the flier blocks may, as intimated, be of any suitable type, being either demountable or integral, the former including screw-threaded means or caps as well as bayonet jointed members.

It will now be appreciated that there has been provided certain novel improvements in flier constructions for spinning machines and more particularly certain improved demountable anti-balloon devices adapted for use with flier arms 50 of any approved type and without requiring the formation of a new unit every time it is desired to change to an anti-balloon construction or vice versa.

What is claimed is:

1. In combination with a flier block having a wire retaining platform, a flier wire and means for clamping the wire to the platform, a detachable anti-balloon device formed of wire and comprising a looped thread guiding member provided with support arms having extensions 60 formed at their free ends, said extensions being received by the retaining platform and held in position thereon by the said clamping means.

2. A flier assembly for spinning machines comprising the combination of a flier block having a flier wire retaining platform, a flier wire seated on said platform, means for clamping the wire

to the platform and a detachable anti-balloon device comprising a thread guiding member having support arms provided with extensions at the free ends thereof, said extensions being held in position on the platform by the flier wire clamping means.

3. A flier wire assembly for spinning machines comprising the combination of a flier block having flier wire retaining means, a flier wire mounted on said block and a detachable anti-balloon device comprising a thread guiding member having support arms provided with extensions at the free ends thereof, said extensions being held in position on the block by mutual engagement with the block and the flier wire mounted thereon.

4. A flier wire assembly for spinning machines comprising the combination of a flier block having flier wire retaining means, a flier wire mounted on said block and a detachable thread guide and anti-balloon device comprising a doubly looped top portion substantially rectangular in shape and provided with side arms, the side arms being provided with bottom extensions at their free ends adapted for mutual engagement with the flier block and the flier wire mounted thereon.

5. A flier assembly for spinning machines comprising the combination of a flier block having a flier wire retaining platform, a flier wire seated on said platform, means for clamping the wire to the platform and a detachable thread guide and anti-balloon device comprising a doubly looped top portion substantially rectangular in shape and having side arms, the side arms being provided with bottom extensions at the free ends thereof, said extensions being held in position on the platform by the flier wire clamping means.

6. A flier assembly for spinning machines comprising the combination of a flier block having a flier wire retaining platform, a flier wire seated on said platform, means for clamping the wire to the platform and a detachable anti-balloon device comprising a top portion constituting a thread guiding member, supports for said member, extensions formed on the free ends of the supports adapted for engagement with a flier block, said supports being formed so as to lie out of the normal path of travel of the thread.

7. In combination with a flier block, a flier wire and means for securing the wire to the block, a detachable anti-balloon device formed of wire and comprising a looped thread guide member provided with support arms having extensions formed at their free ends, said extensions being received by the block.

8. In combination with a flier block, a flier wire and means for securing the wire to the block, an anti-balloon attachment comprising a top portion constituting a thread guiding member, supports for said member, extensions formed on the free ends of the supports adapted for engagement with the block, said supports being formed so as to lie out of the normal path of travel of the thread.

MICHAEL J. McHALE.

70. A flier assembly for spinning machines comprising the combination of a flier block having a flier wire retaining platform, a flier wire seated on said platform, means for clamping the wire
